CLAIM

The ornamental design for a wire frame rack for dishwasher, as shown and described.

DESCRIPTION

FIG. 1 is a perspective view of a wire frame rack for dishwasher according to an embodiment of my new ornamental design;

FIG. 2 is a front view thereof;

FIG. 3 is a left side view thereof;

FIG. 4 is a right side view thereof;

FIG. 5 is a top view thereof; and,

FIG. 6 is a bottom view thereof.

One or more views may not be shown as those views are unornamented or simply not claimed.

The broken lines represent environmental structure or unclaimed portions of the rack and do not form a portion of the claimed design.

The dotted lines represent the border between claimed and unclaimed subject matter and do not form a part of the claimed design.
